UNITED STATES PATENT OFFICE.

WILLOUGHBY R. FLETCHER, OF BRINKMAN, OKLAHOMA.

BALING-PRESS.

1,385,439.

Specification of Letters Patent. Patented July 26, 1921.

Application filed March 22, 1920. Serial No. 367,902.

To all whom it may concern:

Be it known that I, WILLOUGHBY R. FLETCHER, a citizen of the United States, residing at Brinkman, in the county of Greer 5 and State of Oklahoma, have invented a new and useful Baling-Press, of which the following is a specification.

This invention relates to devices employed for compressing various commodities into condition for applying bale bands thereto, and commonly known as baling presses. The improvements are more particularly applicable to cotton baling and compressing apparatus, and for the purpose of illustration the improvements are shown thus applied, but it will be understood that the invention is not necessarily limited thereto, or to any specific form of press, and the right is therefore reserved of applying the improvements to any form of press and to presses employed for any purpose and to which it is applicable.

The object of the invention is to simplify and improve the construction of devices of this character and increase the efficiency without increasing the expense or complication of parts, and to this end the invention consists in certain novel features of construction as hereinafter shown and described and specified in the claims.

In the drawings illustrative of the invention in which corresponding parts are denoted by like designating characters;

Figure 1 is a longitudinal sectional elevation.

Fig. 2 is a transverse sectional elevation, on the line 2—2 of Fig. 1.

Fig. 3 is a sectional detail of the plunger and one of the traveling nuts and the toggle 40 levers illustrating the construction and action.

Fig. 4 is a perspective view of the follower head, detached.

The improved device may be applied with slight and unimportant modifications to nearly all the ordinary forms of baling presses, but for the purpose of illustration is shown applied to an ordinary form of cotton press, in which 10 represents the base frame upon which the press box 11 is supported by a vertical intermediate frame 12, the latter carrying a screw shaft 13, centrally mounted for rotation by spaced bearings 14—15 beneath the press box and carrying a bevel gear 16 between the bearings, as shown.

The ends of the screw protruding from beyond the bearings 14—15 are threaded in reverse order or right and left handed, as shown, and the ends are provided respectively with nuts 19—20, the latter having sockets 21—22 respectively in their lower ends in alinement with the screw shaft, and in their upper sides with spaced sockets 23—24, as shown.

Beneath the screw 13 upon the base frame 10 a track member 25 is carried, and mounted for rotation, as by journals 26—27 in the sockets 21—22, are rollers 28—29 bearing upon the track, as shown.

Movable in the press box 11 is a follower head 30 having spaced sockets 31—32 near its ends and with spaced studs 33—34 extending therefrom, and resting upon the carrier head is a block 35 having spaced apertures through which the studs extend and above whose upper surface they protrude, as shown.

A follower plate 36 rests upon the block 35 and is provided with recesses to receive the protruding ends of the studs, as shown, and by which means the follower plate is supported detachably in position relative to the follower head and its block.

Journaled by their upper ends, as by pins 37—38, in the spaced socket 31—32 and likewise by their lower ends, as by pins 39—40, in the sockets 23—24, are toggle levers 41—42 arranged in pairs and spaced apart corresponding to the spaces between the sockets 31—32 and 23—24.

The ends of the toggle levers will preferably be concentric to their pivot pins, and will engage the bottoms of their respective sockets, so that the strain and end thrust 95 will be borne by the levers, and the pins thereby relieved from the strains, as hereafter more fully explained.

The drive shaft is represented at 43 and mounted as by bearings 44 upon the base frame 10 and carrying a bevel pinion 45 for engagement with the bevel gear 16, the bevel gear 45 being preferably the smaller to secure an increase of power between the shaft 43 and screw 13, as will be obvious.

Any suitable motive power may be applied to the shaft 43, and it may be rotated at any required or suitable speed.

The press box is of the usual shape and is shown formed with two receptacles for 110 the material to be compressed mounted to swing upon a central clamp rod 46 and held

in position by spaced clamp bolts 47 and clamp frame 48 in the usual manner, so that one press box may be supplied with the material to be compressed while the material is being compressed in the other, as will be obvious.

By this arrangement of parts a very powerful pressure may be exerted upon the follower plate and the strains so uniformly distributed that no danger exists of fracturing or straining the screw and other parts.

It will be noted that the lateral thrust and strains are borne entirely by the nuts 19—20, thus relieving the screws entirely of lateral strains and leaving them free to perform their legitimate function of drawing the nuts and the toggle levers inwardly and thus actuate the follower head and plate.

When it is desired to compress bales to a greater extent one or more additional follower plates may be inserted either above or below the bale and the toggle levers again actuated, with the result of decreasing the size of the bale, to an extent equal to the thickness of the additional follower plate or plates.

Having thus described the invention what is claimed is:

1. The combination with a baling press having a press box mounted upon a supporting frame, a screw reversely threaded at its opposite ends and mounted for rotation in said frame, a supporting track carried by said frame parallel to said screw and spaced therefrom, nuts carried by the reversely threaded end of said screw and bearing on said track and toggle levers connected to the nuts, of a follower head movable in said

press box and having spaced guide studs extending therefrom, and a follower plate carried by said follower head and having spaced cavities for engagement with said guide studs, said toggle levers being pivoted by their respective ends in said nuts and follower head.

2. The combination with a baling press having a press box mounted upon a supporting frame, a screw reversely threaded at its opposite ends and mounted for rotation in said frame, a supporting track carried by said frame parallel to said screw and spaced therefrom, nuts carried by the screw and bearing on said track and toggle levers connected to the nuts, of a follower head movable in the press box, a bearing block carried by said follower head, a follower plate carried by the bearing block and means carried by the follower head for retaining the bearing block and follower plate in position on the follower head said toggle levers being pivoted by their respective ends in said nuts and follower heads.

3. In a device of the class described a press box, a follower head mounted for movement in said press box, and a bearing block carried by the follower head, the follower head and bearing block having interengaging elements whereby the bearing block is retained in position on the follower head.

In testimony that I claim the foregoing as my own, I have hereto affixed my signature in the presence of two witnesses.

WILLLOUGHBY R. FLETCHER.
